J. E. COVEY

SMOKE BOX

Filed March 10, 1928

Inventor
John E. Covey

Witness 1
Martin F. Olsen

UNITED STATES PATENT OFFICE.

JOHN ELLSWORTH COVEY, OF CHICAGO, ILLINOIS, ASSIGNOR TO SWIFT & COMPANY, OF CHICAGO, ILLINOIS, A CORPORATION OF ILLINOIS.

SMOKE BOX.

Application filed March 10, 1928. Serial No. 260,613.

This invention relates to smoke producing devices for use in supplying smoke for treating meat.

The objects of the invention are to provide means for avoiding the inconvenience and lack of suitable controlling means in the customary arrangements for producing the smoke for smoke houses and to prevent the escape of soot and ashes into the smoke house and settling onto the meat.

A further object of the invention is to provide a device of this class in which the air supplied thereto may be regulated or limited so that the sawdust fuel is burned at the desired slow rate and more or less blanketed by an unignited covering of sawdust in a self-feeding fuel supply arrangement. It is also an object of the invention to utilize a portion of the unignited sawdust fuel for filtering soot and ashes from the smoke which passes upwardly therethrough into a smoke tube leading to the smoke room. It is also an object of the invention to provide a smoke tube or passage having means for effectually holding back and collecting sparks in case combustion is permitted to take place at too high a rate.

These objects are accomplished by a construction such as shown in the accompanying drawings in which:

Figure 1 is a view in elevation and partly in section of the improved smoke box.

Fig. 2 is a sectional plan view taken on the line 2—2 of Fig. 1.

Fig. 3 is a plan view of the air distributor.

The customary method of producing smoke for smoke houses is to burn sawdust and wood on the floor of a brick-lined room or cell without any reliable means for controlling the quantity of smoke produced or preventing soot and ashes from going up into the smoke house, and settling on the meat.

The present device consists of an entirely closed arrangement, except for the smoke outlet and an inlet at the bottom for air under pressure. The combustion chamber is mounted upon a metallic ash pit or rectangular base. Suitable shaking grates are provided between the combustion chamber and the ash pit. The combustion chamber is preferably lined with firebrick to prevent warping thereof but also to provide insulation for retaining the heat in the fuel. The combustion chamber preferably flares outwardly from the bottom thereof towards the top and a similar

flaring hopper forms a continuation thereof. This hopper is the fuel magazine and is closed at its upper end by removable covered plates, except for a central opening through which passes a smoke tube. This smoke tube extends downwardly into the combustion chamber to about ten inches above the grate and may be rotated on its axis. Suitable means are provided for rotating or oscillating the smoke tube and it has spurs or agitating arms extending outwardly from its side into the fuel in the hopper. Its upper end is enlarged and covered with a hood spaced upwardly therefrom so that means are provided to collect the soot or dust, and it acts as a spark arrester.

Referring to the drawings, the base 1 of the smoke box may be a rectangular metallic structure having a door 2 which is lined with an asbestos gasket 3 for making an air-tight fit. The door is held in place at one side of the ash pit by being provided with a strap iron 4, the projecting end 5 of which is wedge-shaped and passes through a slot in a bracket 6 on the side of the ash pit casing. Suitable latching means are provided between the casing and the opposite end of the door. The handle for the ash pit door is indicated at 7. A removable ash box 8 is located in the ash pit.

Mounted upon the ash pit structure 1 is a rectangular grate support 9 provided with grate shaft bearings and stuffing boxes 10 and preferably lined with fire-brick. The grate shafts 12 and 13 are connected by the gears 14 and a shaker handle 15 is secured to the grate shaft 12.

The combustion chamber 16 is shown as of conical form, composed of the metallic shell 17 lined with fire-brick 18.

The fuel hopper 19 is also of conical form and is a continuation of the combustion chamber but need not be lined with fire-brick as the sawdust fuel therein will provide the necessary insulation. The upper end of the hopper 19 carries inwardly extending braces 20, the inner ends of which are connected by a ring 21. Also at the inner ends of the braces and welded thereto is a ring 22 for rotatably supporting the smoke tube. The smoke tube 23 is wide at its upper end 24 to extend over and rest upon the ring 22. Passing through the enlarged end 24 of the smoke tube is a rod 25 by means of which the smoke tube may be rotated or oscillated for the pur-

pose of preventing any tendency of the sawdust fuel to stick together and not feed properly into the combustion chamber. To this end the tube 23 is provided with spines or 5 agitator arms 26 extending outwardly therefrom to within a few inches of the side of hopper 19. The enlarged end 24 of the smoke tube serves to collect ashes or sparks, if any pass upwardly therein; and to prevent a direct flow of smoke outwardly from the tube. 10 The latter is preferably provided with a hood 27, resting on the upper edge of the part 24 thereof through the forked feet 28 which are riveted to the hood. These feet serve to space the hood the desired extent from the upper edge 29 of the part 24 of the combustion tube.

15 The hopper 19 is closed at its upper end between the combustion tube and the outer edge thereof by the two removable cover plates 30 extending from the periphery of the hopper to the ring 28 on brackets 20.

20 Air is supplied to the fuel by means of a distributing perforated ring-shaped conduit 25 31 located in the ash pit below the grates 32 on the shafts 12 and 13. Air is supplied to the distributor 31 through conduit 34 under the control of a regulating valve 35.

25 In operating the smoke box, in case it is not supplied with gas ignition means, combustion may be started by dropping live coals through the hopper on to the grate before the hopper is loaded with the sawdust fuel. The sawdust fuel collects above the grate and below the smoke tube 23, thereby acting as a filtering bed above the burning part of the fuel on the grate. The flow of air under pressure to the distributor 31 regulates the rate of 30 combustion, valve 35 being provided for this purpose. The air supplied is insufficient to produce rapid and complete combustion and therefore great quantities of smoke are produced. This smoke is filtered as it makes its way through the unignited sawdust to the 35 smoke tube 23. The unignited fuel, therefore, serves to hold back ashes, soot or sparks. Thus the smoke delivered to the smoke house is filtered and clear, and prevents an undesirable accumulation of ashes or soot on the meats being treated. Once the valve 35 is 40 properly set, an occasional operation of the shaker 15 serves to maintain the desired rate of combustion.

45 Although but one specific embodiment of this invention has been herein shown and described, it will be understood that details of the construction shown may be altered or omitted without departing from the spirit of this invention as defined by the following 50 claims.

I claim:

1. A smoke box of the class described, comprising a hollow base for receiving ashes, a combustion chamber mounted above said base, a grate between said combustion chamber and base, a fuel hopper mounted above said combustion chamber, means for closing the upper end of said fuel hopper and a smoke tube extending from the upper end of said hopper downwardly into the combustion 70 chamber.

2. A smoke box of the class described, comprising a hollow base for receiving ashes, a combustion chamber mounted above said base, a grate between said combustion chamber and base, a fuel hopper mounted above said combustion chamber, means for closing the upper end of said fuel hopper, a smoke tube extending from the upper end of said hopper downwardly into the combustion 80 chamber, said smoke tube being mounted for rotation on its axis, and fuel stirring arms extending from the sides of said tube.

3. A smoke box of the class described, comprising a hollow base for receiving ashes, a 85 combustion chamber mounted above said base, a grate between said combustion chamber and base, a fuel hopper mounted above said combustion chamber, means for closing the upper end of said fuel hopper, a smoke tube extending from the upper end of said hopper downwardly into the combustion chamber, and means under the grate for supplying air 90 under pressure.

4. A smoke box of the class described, comprising a hollow base for receiving ashes, a combustion chamber mounted above said base, a grate between said combustion chamber and base, a fuel hopper mounted above said combustion chamber, means for closing the upper end of said fuel hopper, a smoke tube extending from the upper end of said hopper downwardly into the combustion chamber, and an air distributor under the 100 grate.

5. A smoke box of the class described, comprising a combustion chamber and a fuel hopper extending upwardly from said combustion chamber and flaring outwardly towards its upper end, a cover for said fuel hopper, a smoke tube rotatably mounted in said hopper and extending from the combustion chamber through said cover, a hood at the outlet end of said smoke tube, fuel agitator arms extending from the side of said smoke tube, and means for rotating said smoke tube.

Signed at Chicago this 7th day of March, 115 1928.

JOHN ELLSWORTH COVEY.
